UNITED STATES PATENT OFFICE.

JOSEPH C. KRIHA, OF RAVENNA, NEBRASKA.

ADJUSTABLE FORK-SOCKET.

1,107,970.

Specification of Letters Patent. Patented Aug. 18, 1914.

Application filed March 10, 1914. Serial No. 823,757.

To all whom it may concern:

Be it known that I, JOSEPH C. KRIHA, a citizen of the United States, residing at Ravenna, in the county of Buffalo and State of Nebraska, have invented new and useful Improvements in Adjustable Fork-Sockets, of which the following is a specification.

The invention relates to a socket forming the terminal of a fork handle and constructed to adapt its coöperation with and reception of a plurality of forks of different types, whereby the same handle may be used, for example, with many types of forks used in handling different materials.

The main object of the present invention is the provision of a fork handle socket provided with means to interlock therewith any one of a plurality of types of forks, whereby the fork as a whole may be changed to suit requirements.

The invention in the preferred form of details will be described in the following specification, reference being had particularly to the accompanying drawings, in which:

Figure 1 is a perspective view of the improved socket showing one type of fork therein. Fig. 2 is a longitudinal central section of same. Fig. 3 is a transverse section on line 3—3 of Fig. 2. Fig. 4 is a transverse section on line 4—4 of Fig. 2. Fig. 5 is a broken perspective of the fork showing the means applied thereto for coöperation with the socket.

In carrying out the present improvement, the socket 1 which is formed at one end for coöperation with the handle 2 in the usual manner, is formed at the opposite end with a longitudinally extending channel or recess 3 and at the extreme outer end with a transverse notch 4 extending entirely across the socket and communicating with the channel 3.

In rear of the forward end the upper portion of the socket is cut away throughout its full width and to a depth to expose the channel 4 forming what may be termed a locking element receiving recess 5. The respective end walls of the recess in line with the channel 3 are undercut at 6 and 7, forming locking shoulders for a purpose which will be hereinafter described.

The locking element comprises a plate 8 of a size to fit within the receiving recess 5 and shaped on its outer side to complete the formation of the socket at this point. The plate 8 is formed at its forward end with a

locking nose 9 designed when the plate is in position to engage beneath the locking shoulder 6, whereby the forward end of the plate is secured in position. The locking nose 9 is formed with a depending locking projection 10 for a purpose which will presently appear. The rear portion of the plate 8 is formed with a channel 11, the forward portion in advance of the channel being of reduced thickness for a portion of its length to provide a tongue 12 in line with the channel. Pivottally supported between the walls of the channel 11 and resting in said channel is a locking lever including an operating or handle section 13 and a depending or locking section 14 formed with a rearwardly projecting locking nose 15 designed when the parts are in locking coöperation to engage beneath the rear locking shoulder 7 of the socket. The locking projection 14 is formed on its forward edge with an operating projection 16 and a leaf spring 17 is secured on the bottom of the tongue 12 with its rear free end resting on the projection 16.

The forks of the types for coöperation with the improved socket have rearwardly extending rod-like projections 18, the cross bars 19 of the forks being of a size to fit in the transverse recess 4, the rod projections 18 being of a size to fit in the channel 3. The upper surface of the rod-like projection is formed with a notch 20 designed when the cross bar of the fork is seated in the channel 4 to rest directly beneath the locking shoulder 6. With the parts in this position, the locking member 8 is applied, the locking projections 9 and 10 engaging respectively beneath the shoulder 6 and in the recess 20, the rear locking projection 15 engaging beneath the shoulder 7. When it is desired to release the fork for the substitution of another, the operating handle 13 is elevated against tension of the spring 17, removing the rear projection 15 from the locking shoulder 6 and forming a locking plate as an entirety to be raised from the receiving recess 5 to permit withdrawal of the fork and substitution of another.

The improvement described provides a simple device which will readily adapt a single socket for the reception of a plurality of forks of distinct varieties whereby one handle may be made to serve in use with all such forks.

What is claimed is:

1. A handle socket formed with a recess, a

- fork having a projection to seat in said recess and a movable locking element coöperating with the socket to lock said projection thereto, said element comprising forward 5 and rear locking members adapted for coöperation with the socket, and means for moving one of said members with relation to the other to release the element.
2. A handle socket formed with a recess, a 10 fork having a projection to seat in said recess, and a movable locking element coöperating with the socket to lock said projection thereto, said element comprising a plate having forward locking member to coöper- 15 ate with the socket, an additional locking projection to coöperate with the fork, a rear locking projection to coöperate with the socket, and means for moving said latter projection.
- 20 3. A handle socket formed with a recess, a fork having a projection to seat in said recess, a movable locking element coöperating with the socket to lock said projection there- 25 to, said element comprising a plate having forward locking member to coöperate with the socket, an additional locking projection

to coöperate with the fork, a rear locking projection, to coöperate with the socket, means for moving said latter projection, and a spring for normally holding said latter 30 projection in locking position.

4. A handle socket formed with a recess, a fork having a projection to seat in said recess, a movable locking element coöperating with the socket to lock said projection there- 35 to, said element comprising a plate having a forward locking member to coöperate with the socket, an additional locking projection to coöperate with the fork, a rear locking projection to coöperate with the 40 socket, means for moving said latter projection, said socket being formed with receiving recess in which the element is adapted to be inserted, the respective end walls of the recess being formed with locking shoulders to 45 coöperate with said locking projections.

In testimony whereof I affix my signature in presence of two witnesses.

JOSEPH C. KRIHA.
